UNITED STATES PATENT OFFICE

HOWARD R. REIMARD AND VAUGHN A. STARR, OF DANVILLE, PENNSYLVANIA, AS
SIGNORS TO STARR SILK COMPANY, INCORPORATED, OF DANVILLE, PENNSYLVANIA

SPRING-TENSION APPLIANCE FOR LOOMS

Application filed February 2, 1929. Serial No. 337,152.

This invention relates broadly to a loose reed mechanism for looms and more particularly to an auxiliary accessory or spring tension appliance which is made for cooperation with a relatively stationary batten frame and a swingably mounted cooperable reed frame which is carried thereby.

In order to provide for the making of a closer fabric and a more uniform texture and to avoid imperfections, we have evolved and produced a supplemental or auxiliary appliance in the form of an attachment which compensates for irregular filling and also for a lost pick caused by the filling breaking or running out. Naturally, when the filling breaks and the loom is restarted, there will be an irregularity in the spacing of the filler threads, and unless it is remedied a streak or defective spot will occur in the cloth.

20. In the ordinary mechanism used for the purpose mentioned the reed is so constructed that it will always give or spring back a short distance in beating up the filling except when the filling breaks or runs out in which case 25 it does not spring back and forth, thus making up for the lost pick.

What we do is to provide an attachment comprising a bracket made for connection with a batten frame, wherein this bracket 30 functions as a mounting for an adjustable spring, and we make the spring with the tension producing arm, thus developing a device for maintaining a constant spring tension against the reed frame to compensate for the defect and the regularities heretofore encountered.

Briefly described, the mounting is of general U-shaped form and is adapted to be rigidly fastened to the batten frame, and it 40 is provided with a novel manually adjusted axle and bushing arrangement which forms a hub around which the tension spring is coiled, means being embodied in this arrangement whereby the tension of the spring may 45 be varied and maintained in a dependable manner against slipping.

In the drawings:

Figure 1 is a fragmentary end view of a portion of the batten and reed frame together with the appliance associated with

these parts and assuming operative relation.

Figure 2 is a vertical sectional view taken approximately upon the plane of the line 2—2 of Figure 1.

Figure 3 is a horizontal sectional view on an enlarged scale taken approximately upon the plane of the line 3—3 of Figure 1.

Figure 4 is a cross sectional view through the spring anchoring bushing.

In the drawings the reference character 5 designates the relatively stationary upright of the batten frame, and 6 designates generally the pivotally or swingably mounted reed frame.

The appliance comprises the U-shaped 65 brackets 7 which are rigidly bolted to the batten frame. One arm 8 as seen in Figure 3 is formed with a square hole through which one end portion of the square shaft 9 extends. This shaft includes a screw threaded reduced 70 portion 10 carrying a binding nut 11.

On the opposite arm 12 is an outstanding toothed segment 13 with which a toothed disc like head 14 is cooperable. This head includes the collar portion 15 pinned or otherwise rigidly fastened to the adjacent end of the shaft. This collar is made into a nut and adapted to be engaged by an ordinary wrench.

Interposed between the arms and surrounding the square shaft is a bushing including a 80 cylindrical portion 16. This portion 16 is cylindrical only on the exterior surface. The bushing also includes an enlarged head at one end provided with diametrically opposite notches 17 in which the inturned end 85 18 of the coiled tensioning spring extends. The end 18 of the spring may be fitted into either of the notches 17. The coiled portions 19 surround the bushing and spacing anti-friction rings 20 are mounted on this portion 90 of the bushing and the coils surround these rings. The spring, as before stated, includes an arm 21 having its lower end offset in a manner to bear against the plate 22 on the swingably mounted reed frame. The arrangement is such that the arm maintains a 95 constant yieldable pressure against the reed frame.

The particular refinement and distinguishable features of this arrangement is the novel 100

means whereby the spring tension may be regulated in a manner to reduce friction on the coils and yet to maintain the arm in a set position, whereby to permit it to function more accurately and in a more efficient and dependable manner.

From the foregoing description and drawings it will be seen that we have evolved and produced what is regarded as a mechanical achievement in the art beyond similar tensioning devices for loose reed motions for looms. It is smooth in operation, positive and dependable in action, efficient in performance in every way and susceptible of fulfilling the requirements of an invention of this class, in a most satisfactory manner. It is thought that persons skilled in the art to which the invention relates will be able to appreciate the advantages and features.

20 Therefore, a more lengthy description is regarded unnecessary.

Minor changes in shape, size, and rearrangement of parts coming within the field of invention claimed may be resorted to in actual practice if desired.

Having thus described the invention, what we claim as new and desire to secure by Letters Patent is:—

1. In a spring tension appliance for looms, 30 a substantially U-shaped attaching bracket, the arms of which are provided with opposite openings, a shaft extending rotatably and slidably through the openings of said arms, a binding nut on one end of the shaft, and 35 coacting means between the opposite end of the shaft and the adjacent arm for holding the shaft positively in adjusted position, a bushing splined on the shaft between the arms, a coiled spring surrounding and anchored to said bushing and confined between said arms, said coiled spring including an extension forming the laterally offset pressure producing arm.

2. In a spring tension appliance for looms, 45 a substantially U-shaped attaching bracket, the arms of which are provided with opposite openings, a shaft extending rotatably and slidably through the openings of said arms, a binding nut on one end of the shaft, and 50 coacting means between the opposite end of the shaft and the adjacent arm for holding the shaft positively in adjusted position, a bushing splined on the shaft between the arms, a coiled spring surrounding and anchored to said bushing and confined between said arm, said coiled spring including an extension forming the laterally offset pressure producing arm, said bushing including an external cylindrical portion, and anti-friction rings surrounding the bushing and confined within the coils of said spring.

3. In a spring tension appliance for looms, 60 a substantially U-shaped attaching bracket, having its arms formed with opposed openings, one arm being provided with an exter-

nal annular toothed segment, a polygonal shaft extending slidably and rotatably through the openings in said arms and having one end screw threaded, a binding nut carried by said screw threaded end and co-operable with the adjacent arm of the bracket, a toothed disc like element on the opposite end of the shaft cooperable with said segment, and including a collar rigidly fastened to the shaft and functioning as a wrench engaging nut, a bushing assembly on the portion of the shaft between said arms and including spacing and anti-friction rings, a spring anchored at one end to said bushing and coiled around the bushing and ring and having an extended laterally offset end portion forming a pressure producing arm which is adapted to bear against a swingable reed frame.

In testimony whereof we affix our signatures.
